B. E. MEACHAM,
OVEN HEAT REGULATOR,
APPLICATION FILED JAN. 3, 1921.

1,421,281.

Patented June 27, 1922.

B. E. Meacham, Inventor

By A. S. Tattison

Attorney

UNITED STATES PATENT OFFICE.

BENJAMIN EDWIN MEACHAM, OF LORAIN, OHIO, ASSIGNOR TO AMERICAN STOVE COMPANY, OF ST. LOUIS, MISSOURI, A CORPORATION OF NEW JERSEY.

OVEN-HEAT REGULATOR.

1,421,281.

Specification of Letters Patent. Patented June 27, 1922.

Application filed January 3, 1921. Serial No. 434,714.

To all whom it may concern:

Be it known that I, BENJAMIN E. MEACHAM, a citizen of the United States, residing at Lorain, in the county of Lorain and State of Ohio, have invented certain new and useful Improvements in Oven-Heat Regulators, of which the following is a specification, reference being had therein to the accompanying drawing.

10 My invention relates to improvements in oven heat regulators, and it pertains to that class of heat regulators for ovens, which are designed to maintain a predetermined degree of heat within the oven for cooking purposes.

It is well known to those skilled in this art that when the oven door is opened for the inspection of the cooking food, or for any other purpose, the temperature of the 20 oven is lowered, thereby materially varying the desired predetermined degree of heat.

It is also well known to those skilled in the art that in the class of oven heat regulators to which this invention pertains, that 25 after the oven has reached the predetermined heat, a full flame is not necessary to maintain the predetermined degree of heat, and as a consequence, the thermo member partially closes the gas valve controlling the 30 burner and holds the flame reduced sufficiently to maintain the heat at the predetermined degree.

One object of my invention is to automatically cause the full opening of the burner 35 valve when the oven door is opened, so that the burner is operating at maximum the instant the oven door is opened, which, to some extent, prevents the cooling of the oven by furnishing an increased heat therein, and 40 the full flame of the burner after the oven door is closed quickly re-establishing therein the predetermined degree of heat.

In this class of oven heat regulators, there 45 is provided a regulating wheel or handle, operative in connection with a suitable dial, whereby the indicating member may be set at the desired degree of heat indicated by the dial, which will move, set, or regulate the thermo member, so that it will control 50 and maintain the fuel valve in proper position to regulate the flame for providing and maintaining the desired degree of heat.

Another object of my invention is to so construct the parts of the heat regulator

that the setting or regulating member is located in the oven door, where it is convenient for operation, immediately in view of the user at the oven door, whereby the degree of heat is also before the user, making errors in setting it less liable to happen, 60 and being frequently before the user, an error in setting will be detected, and it provides an attractive location.

A further object of my invention is to locate not only the regulating member in the 65 oven door, but also the thermo member, so that when the oven door is open, the thermo member is moved into a cooling zone where it is quickly affected and moves considerably towards its normal position, whereby 70 the fuel valve remains open until the thermo member is again heated to the regulated degree, and whereby the full or approximately the full flame of the burner quickly re-establishes the predetermined degree of heat 75 in the oven after the door is closed.

Further objects of my present improvement will appear from the following description.

In the accompanying drawings:

Figure 1 is a front elevation of a gas stove oven, showing the oven door and gas-supply pipe partially in section to expose the operating parts of my present improvement.

Fig. 2 is a vertical central sectional view 85 on the line 2—2 of Fig. 1.

Fig. 3 is a detached top plan view of the contact blocks.

Fig. 4 is a detached front view of the dial indicating member, and its operating handle. 90

My present improvement may be applied to any form of gas oven. For illustrative purposes, I have shown it applied to a stove having an open burner top 1 and an oven 2 there below, provided with the usual door 95

3. I have here shown the oven door 3 pivoted at its lower edge, as at 4, but the location of the door pivot is immaterial to the carrying out of my invention, which is adapted to be used as well with side or top 100 hinged doors, as well as with the bottom hinged door, here shown. Oven doors are usually double walled, that is they are provided with an inner main or body wall 5, and an outer wall 6, usually referred to as 105 the door panel. In carrying out my present improvement, the regulating mechanism and the thermo member are located between

the panel and wall of the door and are, therefore, within the door. In this location it is protected from injury and from being meddled with by unskilled persons.

5 Various forms of regulating and thermo members may be used in carrying out the broad inventive idea of my present improvement, whereby the fuel supply is opened wide when the oven door is opened for providing a maximum flame at the burner, and whereby the thermo member is moved out of the oven and into a cool zone to be quickly affected thereby and moved towards its normal position. Therefore, the mechanism here shown is one mechanical expression of my present improvement, to which I do not limit myself so far as the broad inventive idea is concerned.

20 The mechanical expression which I have here selected as illustrating my broad idea, comprises a vertical lever 7, which has its lower end suitably connected to a disk or other oscillating member 8. As here shown, this member 8 is shown in the form of a disk, 25 which is journaled in a suitable housing 9, and which is attached to or carried by the lower edge of the door-frame 10. The upper end of this lever 7 is provided with a toothed segment 11, with which a pinion 12 meshes. 30 This pinion 12 is carried by a shaft 13 which has its inner end 14 supported by a suitable bracket 15, which depends from the upper edge of the door-frame 10. The outer end of the shaft extends through the door panel 35 6 and is provided with a suitable handle 16, here shown in the form of a fluted or roughened wheel. A pointer or indicator hand 17 has its upper end connected to the shaft 13 and its lower free end resting against the 40 outer side of the curved dial plate 18. The lower end of this dial plate 18 has an L-bend 19, that is riveted or otherwise connected to the door panel 6, below a curved opening 20, which is formed in the door panel. This 45 opening 20 is of a curve corresponding to the curve of the dial-plate 18, and the opening is closed by a suitable transparent member 21 held to the outside of the panel by a suitable housing or member 22. A vertically 50 arranged thermo member 23 has its lower end 24 suitably connected to an arm or projection 25 of the oscillating member 8, whereby when the handle 16 is rotated to carry the pointer hand 17 to the desired degree on 55 the dial 18, the upper free end 26 of the thermo-member 23 is moved either toward or away from the inner end of a valve controlling rod 27. This rod 27 is suitably supported in bearings 28, which are fastened 60 to the wall 5 of the door and are shown in section. The outer end of the rod 27 carries what may be termed a contact block 29, adapted to engage a contact block 30 on the inner end of the valve stem 31. The opposite 65 site end of this valve stem extends into a

valve house 32 and is attached to the fuel controlling valve 33. This valve 33 controls the flow of gas through the pipe 34 to the burner 35. An ordinary hand-operated gas valve 36 is located in the gas supply 37 above the housing 33, whereby the gas may be entirely shut off from the regulating mechanism. A pilot pipe 38 has its lower end 39 adjacent the burner 35, and its upper end 40 communicating with the gas supply 75 above the housing 31, whereby the pilot continues to burn irrespective of the operation of the fuel valve 33.

70 The spring 41 on the inner end of the rod 27 and the spring 42 engaging the fuel valve 80 33, serve to normally hold the fuel valve open.

75 In operation the hand-operated valve 36 is opened and the burner 35 is lighted, which in turn lights the pilot 39. The pointer 17 85 may be either set to the desired degree of heat indicated by the dial 18, before or after lighting the burner 35, the food to be cooked having been placed in the oven, the burner is lighted. The thermo member 23 90 is composed of a combination of metals well known, and which form no part of my present invention, whereby as it becomes heated it curls or bends toward the inner end of the valve controlling rod 27, and its set 95 position by the handle 16 in respect to the rod 27 is such that it will push the rod 27 and operate the fuel valve 33 to maintain the degree of heat within the oven indicated by the position of the pointer 17 on the dial 100 18. In this operation of the thermo member, the fuel valve at first remains wide open until the thermo member begins to act to close the fuel valve by pushing the rod 27, and the fuel valve is partially closed when the thermo member is deflected by the heat of the oven to maintain the heat at the predetermined degree. When the oven door is 105 opened, the thermo member 23 is moved out of contact with the inner end of the rod 27 and the springs 41 and 42 instantly open the fuel valve wide, so that the burner 35 is furnishing the maximum flame while the oven door is open. This increased amount 110 of heat serves to prevent the lowering of the temperature in the oven to some extent, and the thermo member being moved out of the oven, or zone of the heat of the burner, and is equally affected by the cool zone into 115 which it is moved and partially returns to its normal position, the amount of movement of the thermo member depending upon the length of time the oven door is open. By this arrangement the fuel valve is wide open and the burner flame at maximum 120 while the oven door is open, and after the door is closed the open position of the fuel valve is increased from what it was before the door was open, thus increasing the 125 burner flame, which, in some instances, may 130

be up to maximum, whereby the predetermined degree of heat in the oven is quickly reestablished when the oven door is closed.

By this arrangement of parts, I am enabled to prevent the material lowering of the temperature in the oven for any substantial length of time, by the opening of the oven door.

The contact blocks 29 and 30 have their opposite ends tapered as at 29' and 30', whereby they slide by each other in the closing of the oven door when the door has not been opened sufficiently long to materially affect the thermo member 23, to permit 15 the retraction of the rod 27.

Having thus described my invention what I claim and desire to secure by Letters Patent is:—

1. The combination with an oven having 20 a door and a burner, of a fuel valve for the burner, a thermo member affected by the heat of the burner for controlling the fuel valve, and means cooperating with the thermo-member causing the opening of the 25 fuel valve when the oven door is opened.

2. The combination with an oven having a door and a burner therefor, of a fuel valve for the burner, a thermo member affected by the oven heat and controlling the fuel 30 valve, means controlled by the oven door and cooperating with the thermo-member causing the opening of the fuel valve when the oven door is open.

3. In a mechanism of the character described, an oven having a door, a burner for the oven, a fuel valve for the burner, a thermo member affected by the oven heat and controlling the fuel valve, and means controlled by the oven door for breaking the 40 operative connection between the thermo member and the fuel valve when the oven door is opened, for the purpose described.

4. A mechanism of the character described, comprising an oven having an oven door, a 45 burner for the oven, a fuel valve for the burner, a thermo member operatively connected with the fuel valve for controlling it, and means for breaking the operative connection between the thermo member and the 50 fuel valve when the oven door is open, for the purpose described.

5. A mechanism of the character described, comprising an oven door and a burner for the oven, a fuel valve for the burner, a 55 thermo member operatively connected with the fuel valve, and means co-operating with the thermo-member for moving the thermo member out of the heat zone of the oven and opening the fuel valve when the oven door is open.

6. A mechanism of the character described, comprising an oven having an oven door, a burner, a fuel valve for the burner inde-

pendent of the door, and a thermo member carried by the oven door and operatively 65 connected with the fuel valve, whereby the valve is operated by the opening of the door.

7. A mechanism of the character described, comprising an oven, having an oven door, a burner therefor, a fuel valve for the 70 burner independent of the door, a thermo member carried by the oven door, and operatively connected with the fuel valve when the door is closed, but out of operative connection with the fuel valve when the door 75 is open.

8. A mechanism of the character described, comprising an oven having an oven door, a fuel valve outside of the door, a thermo member carried by the door, a two-part connection between the thermo member and the fuel valve, one part of the connection carried by the oven door, whereby when the oven door is opened the fuel valve is permitted to 80 also open.

9. A mechanism of the character described, comprising an oven having a door, a burner therefor, a fuel valve outside of the door, a thermo member carried by the door, a two-part connection between the thermo member 90 and the fuel valve, one part carried by the oven door, and contact blocks between the adjacent ends of the two part connection, the contact blocks having tapered ends, for the purpose described.

10. A heat regulating mechanism for an oven comprising a burner, a fuel valve therefor, a thermo-mechanism carried by the door and movable laterally with the door, an endwise movable member carried by the 100 door and adapted to be engaged by the thermo-member, a valve stem independent of the door and adapted to be engaged by the adjacent end of the endwise movable member when the door is closed and disengaged when the door is open.

11. A heat regulating mechanism for an oven, comprising an oven having a latterly swinging door carrying a thermo-mechanism, a fuel valve independent of the door and 110 adapted to be closed by the heating of the thermo-mechanism when the door is closed, and the fuel valve opened when the door is moved latterly open.

12. A heat regulating mechanism for 115 ovens, comprising an oven door carrying a vertical rod pivoted at one end to the door, a vertical thermo-member connected with the pivoted end of the rod, a fuel valve independent of the door, and means between the 120 thermo-member and the valve for operating the latter when the door is opened and closed.

In testimony whereof I hereunto affix my signature.

BENJAMIN EDWIN MEACHAM.
